UNITED STATES PATENT OFFICE.

MORGAN J. LEWIS, OF MASSILLION, OHIO.

DOOR CATCH.

Application filed June 3, 1926. Serial No. 113,475.

The invention relates to door catches provided with a pull or push knob whereby the catch will automatically latch the door in closed position and will be released by a 5 pull or push upon the knob to open the door.

- The object of the invention is to provide a door catch including a pivoted latch member operated by a spring to automatically engage the striker, upon the door casing, 10 when the door is closed, a knob for opening the door being operatively associated with the pivoted latch member whereby a pull or push upon the knob to open the door will simultaneously release the latch member 15 from engagement with the striker; a fastener member being associated with the latch member for rendering the knob inoperative whereby the latch may be held in fastened position against movement of the knob. 20 An embodiment of the invention is illustrated in the accompanying drawing, in which

Figure 1 is a horizontal sectional view through a portion of a door and door casing showing the improved door catches as especially designed for use upon screen doors and the like;

Fig. 2, a detached perspective view of the attaching plate;

Fig. 3, a similar view of the pivoted latch operating lever;

Fig. 4, a detail perspective view of the pivoted latch member, showing the lock member thereon, and

Fig. 5, a view similar to Figure 1 showing the form of catch adapted for use upon cupboard doors and the like.

Similar numerals of reference indicate corresponding parts throughout the drawing.

Referring first to the structure shown in Figs. 1 to 4 inclusive, in which the catch is especially adapted for use upon screen doors and the like, a portion of the swing side of the door is shown at 1 and the adjacent part of the door casing at 2. The attaching plate 3 may be of substantially cross shape as shown in Fig. 2, the cross arms 4 being provided with openings 5 to receive attaching screws 6 or the like.

The inner end portion of this attaching plate is provided with an opening 7 through which the knob shank 8 is slidably mounted, a corresponding aperture 9 being provided 55 through the door and a bushing or sleeve 10

located therein for slidably receiving the shank upon each end of which may be mounted a knob 11 adapted for pulling or pushing the door open upon its hinges in the usual manner.

A pair of angular ears 12 are formed upon the outer end portion of the attaching plate, the end portions of these ears being rounded as shown at 13.

The latch operating lever 14 is provided with a pair of angular ears 15, pivotally connected to the ears 12 as by the pin 16. The free end portion of this lever is arcuate, as shown at 17 for engagement with the inner knob and provided with the slot 18 which receives the knob shank 8.

The latch member 19 is provided with the angular end portion 20 provided with the spaced angular ears 21 pivoted upon the pin 16 and located inside of the lever 14, 75 the spring 22 normally holding the latch in the position shown in Fig. 1 and urging the same into engagement with the striker 23 upon the door casing 2.

This striker may be provided with the 80 spaced latch keeper portions 24, thus providing means for latching the door in the event it does not entirely close, this feature being especially useful for screen doors as the door will be held latched in closed position in the event it is not fully closed.

A cam locking member 25 is pivotally mounted upon the latch member as by the bolt or pin 26, a coil spring 27 surrounding the same and placing sufficient tension thereon to hold the locking cam in adjusted position. A finger piece 28 may be formed upon the locking cam for easily operating the same.

With the locking cam in the position shown in Figs. 1 and 4, the flange portion 29 thereof normally engages the end portion of the operating lever 14. Thus an outward pull or push upon the knob shank 8, in the direction of the arrow shown in Fig. 1, will 100 rock the lever 14, upon the pivot 16, moving the latch member 19 in the same direction and releasing the latch from the striker.

If the locking cam is given a quarter turn, so that the flange portion 30 thereof assumes 105 the dotted line position shown in Fig. 1, the operation of the knob shank 8 will merely rock the lever 14 upon its pivot without affecting the latch member which will be held in the latched position by the spring 110

22. Thus the door may be effectually fastened so that it cannot be opened from the outside.

In the form of catch shown in Fig. 5, 5 which is especially adapted for use upon cupboard doors and the like, the fastening cam is eliminated. In this form of the invention the door 1, casing 2, attaching plate 3, shank 8, bushing 9 and knob 11 may be 10 substantially the same as in the form above described with the exception that only the outer knob is provided upon the shank as doors of this kind are not designed to be 15 operated from the inside. The lever 14^a and latch 19^a are integral or rigidly connected together and the striker 23 may if desired be of the double form shown in Fig. 1.

The operation of this form of the invention is the same as that described and illustrated above when the fastening cam is in the position shown in Fig. 1; an outward pull upon the knob releasing the catch from the striker.

23. I claim:

1. A door catch including an attaching plate for mounting upon a door and provided with a pair of angular ears, a latch member provided with a pair of angular ears, a pivot pin connecting the ears of the plate and latch member, a striker, a spring between the plate and latch member for normally urging the latch member into engagement with the striker, a lever operatively associated with the latch member, a knob shank slidably mounted through the door and operatively connected to the lever and means for disconnecting the lever from the latch member whereby the latch member will remain engaged with the keeper when the lever is operated.

2. A door catch including an attaching plate for mounting upon a door and provided with a pair of angular ears, a latch member provided with a pair of angular ears, a pivot pin connecting the ears of the plate and latch member, a striker, a spring

between the plate and latch member for normally urging the latch member into engagement with the striker, a lever operatively associated with the latch member, a knob shank slidably mounted through the door and operatively connected to the lever and means upon the latch member for disconnecting the lever from the latch member whereby the latch member will remain engaged with the keeper when the lever is operated.

3. A door catch including an attaching plate for mounting upon a door and provided with a pair of angular ears, a latch member provided with a pair of angular ears, a pivot pin connecting the ears of the plate and latch member, a striker, a spring between the plate and latch member for normally urging the latch member into engagement with the striker, a lever operatively associated with the latch member, a knob shank slidably mounted through the door and operatively connected to the lever and a cam fastener for disconnecting the lever from the latch member whereby the latch member will remain engaged with the keeper when the lever is operated.

4. A door catch including an attaching plate for mounting upon a door and provided with a pair of angular ears, a latch member provided with a pair of angular ears, a pivot pin connecting the ears of the plate and latch member, a striker, a spring between the plate and latch member for normally urging the latch member into engagement with the striker, a lever operatively associated with the latch member, a knob shank slidably mounted through the door and operatively connected to the lever and a cam fastener upon the latch member for disconnecting the lever from the latch member whereby the latch member will remain engaged with the keeper when the lever is operated.

In testimony that I claim the above, I have hereunto subscribed my name.

MORGAN J. LEWIS.
